UNITED STATES PATENT OFFICE.

FRANK R. PEETS, OF MERRILL, NEW YORK.

AUTOMATIC BRAKE.

1,308,105.

Specification of Letters Patent.

Patented July 1, 1919.

Application filed July 31, 1918. Serial No. 247,696.

To all whom it may concern:

Be it known that I, FRANK R. PEETS, a citizen of the United States of America, and a resident of Merrill, in the county of Clinton and State of New York, have invented a certain new and useful Automatic Brake, of which the following is a specification, the same being a full, clear, and exact description of the invention, such as will enable others skilled in the art to which it appertains to make and use the same.

This invention relates to mechanical devices for arresting or retarding the motion of a vehicle by means of friction, and particularly to that class of the same comprising shoes or other brake structures pressed against the rim of the wheels and which operate mechanically—or automatically—under certain conditions of use, and which may be also actuated manually.

The invention comprises a novel arrangement of elements whereby under some circumstances—as where the wagon is traveling on descending ground—the brake is caused to apply itself and therefore to be self-acting. The brake may preferably be also readily rendered inoperative under other conditions, as when the team is backed, so as not to impede the required rearward movement of the vehicle, while at any time desired—as when on a level road—the brake may preferably be applied manually. The object of the invention is primarily to provide a simple, strong, durable and efficient mechanism that shall be operated by the hold-back of the horses on the tongue and shall consist of certain novel features of construction, combination and operation of elements as hereinafter set forth.

In order that the invention shall be fully understood reference may be had to the accompanying drawings, illustrative of one embodiment of the invention, which accompany and form a part of this specification, and in which—

Figure 1 represents an elevation, partly in section, of a device constructed according to my invention; and

Fig. 2 is a plan view of the same.

Like numerals of reference indicate like parts in both the views.

Referring particularly to the drawings, 1 denotes the wheels, 2 an axle, 20 the body and 3 the pole of a wagon. I ordinarily cut

two slots 4 in the pole 3, which slots are preferably elongated in contour and spaced a distance apart. A rod or tube 10 is located adjacent to, and preferably in alinement with, the pole, which rod is preferably connected to, and serves to operate, the brakes 13, the said rod being guided in its movement by suitable devices, as by means of bolts 9 which work in the slots 4.

At the forward end of the rod 10 is secured the neck-yoke 8, and toward the rear extremity of the same is attached the whiffletree 7. The forward strain of the horses, and the consequent forward movement of the rod 10 traveling on the pole 3, takes off the brakes 13 from the wheels. On descending ground, however, the backing of the horses throws back the rod 10, together with the whiffletree 7, and puts on the brakes.

The means by which the said operation and connection of the parts are accomplished may be varied, but a simple and convenient construction by which the said end may be attained comprises the following elements. Plates 5 having central elongated projections are placed above and below the slots 4, which plates may be held together by the bolts 9, by which construction of elements the parts are rendered adjustable and the distance between the plates 5 may be varied at will. Upon the bolts may be swiveled the whiffletree 7 and the neck-yoke 8.

In order to attach the rod 10 to the last named elements in a convenient manner the same are preferably mounted on the bolts 9 and means for connecting the said swiveled parts with the rod may comprise any desired arrangement, as for example, a preferably U-shaped plate 6 having orifices in which the sections of the rod 10 may be screwed, which rod is preferably provided with means for lengthening or shortening the same at will by the use of a turn-buckle 11.

By the employment of the before described adjustable parts, my device may be adapted to be used with poles of varying length, width and thickness, and the accommodation of my invention to poles of different sizes may be attained by merely cutting the slots 4 at suitable distances apart and screwing the pairs of plates toward or away from each other as occasion may require. The lower plates 5 may be integral with the bolts 9, or they may be dispensed with altogether,

and the whiffletree and neck-yoke may also be employed alone without the use of the upper plates 5 if so desired.

The connection or joint at the whiffletree 5 and neck-yoke in the embodiment of the invention illustrated will not work loose for the reason that the plates 5 cannot turn on account of the longitudinal projections thereof, and also as the whiffletree and neck-yoke are prevented from having any undue rotary movement, and are always held in working position, by the rod 10.

In case it is desired to back the wagon without operating the brakes, rearward movement of the rod 10 may be prevented by the mere insertion of a pin 12 in the pole 3 near to or posterior of the rear portion of the whiffle tree. The brakes may be applied either to the forward or rear periphery of the wheel, or to both of the same as may be desired. In the latter case, the inward end of the rod 10 may be connected with a lever 14—the central portion of which may encircle the rear portion of the pole—which lever may operate the rear brakes 13 by means of the intermediate lever 15.

Should it be desired to operate the brakes by hand, this operation may be accomplished by the manipulation of the lever 18, pref-

erably pivoted to the bolster 19, which brake-lever may operate the lever 14 through the intermediate lever 17 and the rod 16.

I wish it to be understood that I do not desire to be limited to the particular use or the exact details of construction shown and described, for obvious modifications will occur to persons skilled in the art.

What I claim as my invention is:—

An automatic brake for vehicles comprising, in combination with the brake and wagon tongue thereof, said tongue having a slot, guide means located below the slot, a brake actuating rod, a whiffle tree, a support for said whiffle tree having a portion positioned in the plane of said rod for attachment of the rod to the whiffle tree support, and a bolt extending through said slot in the tongue and connecting said guide and attaching means and whiffle tree together for slidable movement upon the tongue. 50

In testimony of the foregoing specification I do hereby sign the same in the town of Merrill, county of Clinton, and State of New York, this 17th day of June, 1918.

FRANK R. PEETS.
